DESIGN FOR AN ELECTRIC HEATER

Emile C. Mathis, New York, and Jules Louis Dronet, Brooklyn, N. Y., said Dronet assignor to Matam Corporation, Long Island City, N. Y., a corporation of Delaware

Application May 1, 1945, Serial No. 119,328

Term of patent 7 years

(Cl. D81—10)

To all whom it may concern:

Be it known that we, Emile C. Mathis, a citizen of the Republic of France and resident of the Borough of Manhattan, in the city, county, and State of New York, and Jules L. Dronet, a citizen of the Republic of France and resident of the Borough of Brooklyn, in the county of Kings, city, and State of New York, have invented a new, original, and ornamental Design for an Electric Heater, of which the following is a specification, reference being had to the accompanying drawing, forming a part thereof.

Fig. 1 is an end view, in perspective, of the switch end of an electric heater showing our new design;

Fig. 2 is an end view, in perspective, of the cord end of the heater;

Fig. 3 is a side elevation of the heater, and

Fig. 4 is a top plan view thereof.

We claim:

The ornamental design for an electric heater, substantially as shown.

EMILE C. MATHIS.
JULES LOUIS DRONET.
